Primary Examiner — Holly Baynham(74) *Attorney, Agent, or Firm* — Dorsey & Whitney LLP(57) **CLAIM**

The ornamental design for a luggage, as shown and described.

DESCRIPTION

FIG. 1 shows a front perspective view of a luggage; FIG. 2 shows a front elevation view of the luggage of FIG. 1; FIG. 3 shows a rear elevation view of the luggage of FIG. 1; FIG. 4 shows a right elevation view of the luggage of FIG. 1; FIG. 5 shows a left elevation view of the luggage of FIG. 1; FIG. 6 shows a top view of the luggage of FIG. 1; and, FIG. 7 shows a bottom view of the luggage of FIG. 1. The broken lines in FIGS. 1-7 illustrate the environment of the luggage and form no part of the claimed invention.
